FIG. 4.

UNITED STATES PATENT OFFICE

EDWARD BRUNHOFF, OF WYOMING, OHIO

ADVERTISING CHANGE TRAY

Application filed September 14, 1929. Serial No. 392,674.

My invention relates to improvements in advertising change tray. One of its objects is to provide an improved change tray adapted to serve as a means to advertise, attract attention to and assist in vending articles to be vended. Another object is to provide an improved change tray structure having a receptacle for articles to be vended and adapted to display said article to advantage and to direct attention thereto. Another object is to provide an improved advertising change tray structure partly of glass, porcelain or similar material and partly of metal. Another object is to provide an improved reinforced advertising change tray structure combined partly of glass or similar material and partly of metal. My invention also comprises certain details of form and arrangement, and combination of components, all of which will be fully set forth in the description of the accompanying drawings, in which:

Fig. 1 is a perspective view of an advertising change tray embodying my improvements.

Fig. 2 is a vertical section through the same taken on line 2—2 of Fig. 1.

Fig. 3 is a vertical sectional detail taken on line 3—3 of Fig. 2.

Fig. 4 is a perspective view of a reinforcing member detached.

The accompanying drawings illustrate one embodiment of my invention in which 15 represents a change tray member molded from glass, porcelain, or similar material, for instance transparent glass. The member 15 is provided with an inclined top face 16, an annular rim or ledge 17, a bead 18 around its base and a pocket 19 in which change is designed to be deposited and concentrated, and from which change is adapted to be conveniently removed. The member 15 is also adapted to be ornamented upon its inner face or under face with ornamental designs and colors, including advertising matter, trade marks, and similar illustrations, which show through the transparent material with an added finish and luster, and are housed and kept clean, and the outer face is adapted to be cleaned without injury to the appearance of

the designs and advertising matter. Spaces 20 and 21 are designed to show the trademark and advertising matter relating to the goods to be vended.

A sheet base member 22 has upturned projections 24 upon one end and upon the front and back to enable the member 15 to be slipped laterally into place with its bead 18 engaged by the projections 24 to lock and hold the member 15 to the base member 22 as shown in Fig. 1. A sheet metal tray 25 open at the top and at its front is attached by rivets to the base member 22, with one side of the tray 25 resting against one side of the member 15 so as to lock the member 15 firmly in place relative to the base member 22 and also to lock the tray 25 rigidly to the base member 22. In order to prevent the base member 22 being bent along or close to the line where the tray 25 meets the member 15, I preferably provide a reinforcing member 28 of sheet metal having ribs or offsets 29 or corrugations 30, or both extending beneath the members 15 and 25 and transversely to the line along which the members 15 and 25 meet, to prevent the member 22 being bent or buckled. As illustrated the ribs 29 and corrugations 30 are formed in a piece of sheet metal separate from the base member 22, and attached thereto at its four corners by means of rivets 32 and 33. The rivets 32 have their shanks passed through the base member 22 and the reinforcing member 28 to hold them together. The rivets 33 pass through the lower inturned edge 39 of the tray 25, through the base member 22, and through the reinforcing member 28 to hold the tray, the base, and the reinforcing member together. The rivets 32 and 33 are provided with soft rubber heads 44 extending below the member 28 to serve as a soft cushion support for the change tray and enable it to rest upon the top of a glass show case or varnished counter without injury thereto. If desired the ribs 29 and corrugations 30 may be formed directly in the base member 22, instead of in a separate member. Rivets 38 serve to attach the ledge 39 of the tray 25 to the base member 22 close to the edge member 15.

5 The tray 25 is adapted to be kept filled or partially filled with packages 36 of the goods to be vended, and said packages 36 are designed to also display advertising matter, trade-marks and similar advertising matter relating to the goods to be vended in an attractive manner. The attention of a person reaching to the change tray for his change is particularly directed to the advertising matter and also to the articles in the tray 25 10 ready to be vended.

15 The apparatus herein shown and described is capable of considerable modification within the scope of the claims without departing from the spirit of my invention.

15 What I claim is:

1. A portable support for a plurality of tray members arranged in side by side relation and one of which is of substantially rectangular form, comprising a base member having cushioning means to seat on a counter or like supporting surface, one of said last two named members having projections along two of its ends and one side thereof and the other of said last named members having grooves along its corresponding two ends and sides to slidably receive the projections of the first of said two named members, the other of the tray members being engaged with the opposite side of the rectangular tray member for holding the latter against sliding longitudinally of the base member, and means to rigidly secure said other tray member to the base member thereby to fixedly secure the rectangular member against all movement relative to the base member.

2. A portable support for a plurality of tray members arranged in side by side relation and one of which is substantially rectangular in form and has beads along two of its ends and one side thereof, comprising a base member connecting the tray members having upturned projections engaging each of the beads of the rectangular member, a reinforcing member separate from the base member and secured to the underface thereof and extending across the junctural points of the tray members, and means to connect the reinforcing member to the base member, said connecting means having cushioned surface engaging portions for supporting the base member.

3. A portable support for a plurality of tray members arranged in side by side relation and one of which is of substantially rectangular form, comprising a base member, one of said last two named members having projections along two of its ends and one side thereof and the other of said two last named members having grooves along its corresponding two ends and sides to slidably receive the projections of the first of said two named members, the other of the tray members being engaged with the opposite side of

the rectangular tray member for holding the latter against sliding longitudinally of the base member, a reinforcing member beneath the base member extending across the points of juncture of the tray members, means to rigidly secure said reinforcing member to said other tray member, and to the base member thereby to fixedly secure the rectangular member against all movement relative to the base member, and cushioning means connected to said securing means to seat on a counter or like supporting surface.

In testimony whereof I have affixed my signature.

EDWARD BRUNHOFF.
